(57) **CLAIM**

The ornamental design for a bird figurine, as shown and described.

DESCRIPTION

FIG. 1 is a perspective view of the bird figurine of the present invention showing our new design;

FIG. 2 is a top plan view thereof;

FIG. 3 is a right side elevational view thereof;

FIG. 4 is a front view thereof;

FIG. 5 is a rear view thereof;

FIG. 6 is a left side elevational view thereof; and

FIG. 7 is a bottom plan view thereof;

FIG. 8 is a second embodiment of the bird figurine of the present invention showing our new design;

FIG. 9 is a top plan view thereof;

FIG. 10 is a right side elevational view thereof;

FIG. 11 is a front view thereof;

FIG. 12 is a rear view thereof;

FIG. 13 is a left side elevational view thereof; and,

FIG. 14 is a bottom plan view thereof.

The broken lines represent portions of the article that are not part of the claimed design.
